AUTOMATIC PHONOGRAPH STOP

Application filed April 14, 1928. Serial No. 270,100.

This invention relates to improvements in devices for automatically controlling the operation of sound reproducing apparatus, such as phonographs and the like.

5 The primary object of the invention is to provide an improved friction-brake adapted to engage the circumferential periphery of the rotatable record-table of sound-reproducing apparatus, which friction-brake may by simple connections be released from record-table braking position at a predetermined time under the controlling action of an alarm-clock which may be of any ordinary commercial type.

15 A further object of this invention is to provide a friction-brake of this character by means of which the braking action is increased by any rotation tendency of the record-table.

20 A still further object of this invention is to provide means whereby the automatic release of the friction-brake causes the closing of an electric-circuit which may be employed as a power factor in the operation of the sound-reproducing apparatus or for lighting a lamp, etc.

Other objects of the invention will be apparent from the following description and claims.

30 In a preferred embodiment of the invention, a friction-element carrying lever has its fulcrum within the circumference of the record-table and rearward of a record-table radius through the point of engagement of 35 the friction-element with the circumferential periphery of said table, whereby any rotation tendency in the proper direction of the record table has the effect of increasing the braking action by said lever.

40 Pivotedly carried by the brake-lever to swing about an axis transverse to the axis of said lever is an arm which may be latched to hold the brake-lever in record-table engaging position against the action of a 45 spring. The pivotal latch-arm is connected by means of a flexible element, such as a cord, with the alarm winding-stem of an alarm-clock whereby the latch-arm may be caused to be automatically tripped at a pre- 50 determined time to permit the brake-lever to

be released from the record-table under the action of the lever-spring. Operatively connected with the brake-lever is an electric-current transmitting switch-member which acts to bridge the spaced contact-members of a switch in an electric-circuit, when the brake-lever swings into release position. This electric-circuit may be employed for transmitting current to a motor designed to operate the sound-reproducing apparatus, or it may be employed for any other purpose such as the lighting of a lamp. In its complete form, the present improvement also includes adjustable means for automatically swinging the brake-lever into position to arrest the rotation of the record-table by the inward movement of the tone-arm of the apparatus during or at the completion of the playing of a record upon the record-table.

55 In the accompanying drawings, Fig. 1 is a top-plan view of a portion of a sound-reproducing apparatus to which the present improvement has been applied, the record-table being partly broken away adjacent the brake-lever and the switch-box frame being shown in section. Fig. 2 is an enlarged front-end elevation, partly in section, of the upper portion of the apparatus, omitting the tone-arm. Fig. 3 is a side-elevation 60 of the brake-lever and latch-arm as mounted upon the supporting-plate therefor. Fig. 4 is a detached perspective view of the brake-lever supporting-plate. Fig. 5 is a side view of the switch with the box there- 65 for shown in section.

70 The present improvement is applicable to any of the well known makes of sound-reproducing apparatus and any ordinary alarm-clock may be employed to control the release of the brake.

75 Referring to the drawings, the present improvement is illustrated as applied to a sound-reproducing apparatus including a frame or casing 1 having near its upper end a casing-table 2. Spaced above and parallel to the casing-table 2 is a record-table 3, which may be supported and operated in any usual manner, the present invention being equally applicable to elec- 80

trically and mechanically operated motor-driven apparatus. Capable of travelling across the record-table is the usual sound-box 4, carried by the free end of a tone-arm 5 swinging inwardly toward the axis of rotation of the record-table during the sound-reproducing process.

Secured upon the casing-table 2 underneath the record-table 3, by means of a pivot-screw 6 is a supporting-plate 7 provided with an arcuate slot 8 entered by a securing-screw 9, this construction providing for adjustment of the supporting-plate 7 to change its angular position with respect to a record-table radius. The supporting-plate 7 is provided with a threaded aperture 10 entered by a pivot-screw 11 constituting the fulcrum of a brake-lever 12 capable of swinging about its pivotal axis in a plane parallel to the plane of the record-table. The brake-lever, which in the present instance is made from a sheet-metal blank, may be of any suitable construction and between its ends fixedly carries a friction-element 13 in position to engage the circumferential periphery of the record-table 3, in a swinging movement of the free end of the brake-lever 12 in one direction. The braking surface of the friction-element is preferably disposed tangential to the record-table at the time of engagement of the friction-element therewith.

Considered in the direction of rotation of the record-table, which direction is indicated by the arrow in Fig. 1 of the drawings, the pivotal axis of the brake-lever 12 is rearward of a radius through the point of engagement of the friction-element with the record-table and therefore any rotation tendency of the record-table in its proper direction has the effect of increasing the braking action of the friction-element. Wear of the friction-element may be readily taken up by the before described adjustment of the supporting-plate 7. The swinging movement of the brake-lever in the direction to engage the record-table is preferably limited by a stop-ear 14 upturned from the supporting-plate 7, said stop-ear being slightly spaced from the brake-lever in a normal braking position of said lever. Projecting upwardly from the brake-lever 12 is a thumb-piece 15 for manually swinging the lever into braking position against the action of a spring 16, secured upon the plate 7 and yieldingly bearing against the lever to release it from braking position. At its free end, the brake-lever 12 pivotally carries an elongated, bent latch-arm 17, the pivotal axis of the latch-arm being substantially transverse to the like axis of the lever. A detaining member or latch 18 for the latch-arm is provided by upturning a tongue at the outer end of the plate 7, in a manner to incline it upwardly toward its rear end

whereby the brake-lever may be releasably latched in braking position.

Suitably connected with the free end of the latch-arm, through the intermediary of a coil-spring 19 is one end of a flexible-element or cord 20 of which the opposite end is connected to a crank 21 afforded by the alarm-winding stem of an alarm-clock 22. In the present instance, the alarm-clock is placed between bent clamp-arms 23 secured upon an angle-bracket 24 fixed upon the casing 1 adjacent the brake-lever, but it is evident that any other suitable clock-supporting medium may be employed.

Secured upon the casing-table 2, for adjustment in the direction of the brake-lever is an insulator block 25 adjustably carrying spaced contact-members, as 26, the inner ends, as 27, of which are upturned and are inclined with respect to each other. By suitable binding-posts, these contact-members are connected with current-leads, as 28, of an electric-circuit which may constitute the source of power of the sound-reproducing apparatus or may be employed for any other desired purpose. Suitably connected with the brake-lever 12 by means of a link 29 and an intermediate insulating link 30 is a shiftable switch-member 31 of current-conducting material. At its end nearest the fixed contact-members, the switch-member 31 is formed as a V-shaped bridge 32 adapted to simultaneously engage the upturned ends 27 of said fixed contact-members, when the brake-lever is swung away from the record-table. The switch-member 31 is shown as guided by spaced pins, as 33, fixed upon the insulator-block 25 which is preferably covered by a cap-plate 34.

In order to automatically swing the brake-lever 12 into position to restrain the record-table against rotation, said brake-lever is connected by a cord 35 or the like with the free end of an arm 36 secured upon the lower end of an oscillatory, vertically-aper-tured block 37. Fixed upon the casing-table 2 adjacent the rear end of the tone-arm 5 is a post 38 upon which the block 37 oscillates, said block carrying at its upper end another arm 39. Threaded into the arm 39 is an adjustable screw 40 provided with a buffer-disk 41 of suitable material and positioned to be engaged by the tone-arm as the latter swings inwardly in the usual manner.

The operation of the present device is so simple that it will be clearly understood from the foregoing description. Suffice it to mention that the brake-lever is held in record-table engaging position by the latch-arm 17 and latch 18 to restrain said record-table against rotation if operated by a mechanical motor and to maintain an open circuit if operated by an electric-motor connected with the described switch. By setting the alarm-clock to automatically trip

the latch-arm at a predetermined time, the spring 16 acts to release the brake-lever 12 from engagement with the record-table and thereby shifts the switch-member 31 in a direction to cause its V-shaped end to bridge the spaced contact-members 27 and close the electric-circuit. The record-table being now free to rotate, the tone-arm 5 swings inwardly during the playing of a record and engages the buffer-disk 41 to swing, through the described connections, the brake-lever into record-table engaging position.

Having thus set forth the nature of the invention, what I claim herein is:

1. In a sound-reproducing apparatus having a rotatable record-table, a swinging brake-lever having its pivotal axis within the circumference of said record-table, a friction-element carried by the brake-lever positioned to engage and release the circumferential periphery of said table in swinging movements of the brake-lever in opposite directions, means acting to shift said brake-lever from braking to release positions and means for releasably latching said brake-lever in braking position.

2. In a sound-reproducing apparatus having a rotatable record-table, a swinging brake-lever having its pivotal axis within the circumference of said record-table, a friction-element carried by the brake-lever positioned to engage and release the circumferential periphery of said table in swinging movements of the brake-lever in opposite directions, means acting automatically upon operation of the sound-reproducing apparatus for swinging said lever from release to braking positions, and means for releasably latching said brake-lever in braking position.

3. In a sound-reproducing apparatus having a rotatable record-table, a brake-lever, a pivotal support for said lever, a latch-arm pivotally supported by said lever, a friction-element carried by the brake-lever between its pivotal support and said latch-arm in position to engage and release the periphery of said record-table upon swinging movements of the brake-lever in opposite directions, a stop-element for holding said latch-arm in record-table braking position of the brake-lever, and means for automatically swinging said brake-lever from braking to release positions upon release of said latch-arm.

4. In a sound-reproducing apparatus having a rotatable record-table and a swinging tone-arm, a brake-lever, a pivotal support for said lever, a latch-arm pivotally supported by said lever, a friction-element carried by the brake-lever between its pivotal support and said latch-arm in position to engage and release the periphery of said record-table upon swinging movements of the brake-lever in opposite directions, a

stop-element for holding said latch-arm in record-table braking position of the brake-lever, means for automatically swinging said brake-lever from braking to release positions upon release of said latch-arm, and means for automatically swinging the brake-lever from release to braking positions upon inward movement of said tone-arm.

5. In a sound-reproducing apparatus having a rotatable record-table, a brake-lever, a pivotal support for said lever, a latch-arm pivotally supported by the brake-lever to swing about an axis transverse to the pivotal axis of the lever, a friction-element carried by the brake-lever in position to engage and release the periphery of said record-table upon swinging movements of the brake-lever in opposite directions, means for latching said arm to hold said lever in record-table braking position, and a spring acting to swing said lever from braking to release positions upon release of said latch-arm.

6. In a sound-reproducing apparatus having a rotatable record-table, a friction-brake member capable of being shifted to engage and release said record-table, spaced contact-members of an electric-circuit controlling switch, a spring acting to shift said friction-brake member from record-table engaging position, and means for bridging said spaced contact-members to close the electric-circuit upon shifting of said friction-brake member under the action of said spring to release the record-table.

7. In a sound-reproducing apparatus having a rotatable record-table and a swinging tone-arm, a friction-brake member capable of being shifted to engage and release said record-table, spaced contact-members of an electric-circuit controlling switch, a spring acting to shift said friction-brake member from record-table engaging position, means for bridging said spaced contact-members to close the electric-circuit upon shifting of said friction-brake member under the action of said spring to release the record-table, and means rendered effective by inward movement of said tone-arm for shifting said friction-brake member to engage said record-table and open said electric-circuit.

In testimony whereof, I have signed my name to this specification.

EMIL TRAUB.
